Primary Examiner—Joel Sincavage

Assistant Examiner—T. Chase Nelson

(74) Attorney, Agent, or Firm—Finnegan, Henderson, Farabow, Garrett & Dunner, LLP

(57) **CLAIM**

The ornamental design for a fabric, as shown and described.

DESCRIPTION

The single FIGURE is a top plan view of a fabric showing the repetitive unit of my new design, the fabric having no appreciable thickness and the reverse side of the fabric being non-ornamental. The fabric repeats indeterminately in one or more directions.
